UNITED STATES PATENT OFFICE.

WILLIAM C. EDLER AND FRANK WINDLE, OF PHILADELPHIA,
PENNSYLVANIA.

LOOM.

SPECIFICATION forming part of Letters Patent No. 636,773, dated November 14, 1899.
Application filed February 27, 1899. Serial No. 706,943. (No model.)

To all whom it may concern:

Be it known that we, WILLIAM C. EDLER and FRANK WINDLE, citizens of the United States, residing at the city of Philadelphia, in the county of Philadelphia and State of Pennsylvania, have invented certain new and useful Improvements in Looms, of which the following is a specification, reference being had therein to the accompanying drawings.

10 The object of our invention is to provide a simple and efficient electromagnetic picker mechanism for looms with the view of dispensing with the usual picker-sticks and their many coacting parts.

15 To this end the invention comprises various features of construction and arrangement of parts, which will be hereinafter set out in detail and be duly claimed.

In the drawings, Figure 1 is a vertical section through a portion of a loom embodying our invention in one form thereof. Fig. 2 is a front view of the lay and adjuncts. Fig. 3 is a horizontal section on the line 3-3 of Fig. 2. Fig. 4 is a diagram of the electrical connections. Fig. 5 is a detail of one of the switch-levers, showing the shuttle-clamping arms in section. Fig. 6 is an elevation of one of the shuttles which we prefer to use.

20 A is the framework of the loom; B, the main shaft; B', a counter-shaft geared therewith and provided with a crank b; C, the lay, connected with said crank by a pitman b'; C', the shuttle-race on said lay; D, the vertically-movable shuttle-boxes at the respective ends of the lay, and E one of the shuttles. These parts are of usual and well-known construction, excepting as hereinafter described.

25 The shuttle is the same as heretofore, excepting that a greater quantity of metal is used in its construction—that is, the ends e and bottom e' of the shuttle are constructed wholly of magnetic metal let into the wooden body e². If desired, however, the entire shuttle may be of metal.

30 Suitably disposed on the lay adjacent to the respective shuttle-boxes are two electro-magnets, preferably solenoids, F, through which the shuttle is designed to travel in its passage from side to side of the loom. The solenoids are supported by brackets f, of non-

conducting material, and are energized from a suitable source of electricity, provision being had whereby the respective circuits therefor are made and broken at predetermined intervals in respect to the actions of the lay. Hence if a shuttle be contained in one of the boxes in the horizontal plane of the shed and the adjacent solenoid be energized the shuttle will be attracted into and through the solenoid. If just before the shuttle has been fully attracted by the solenoid the current to the latter be suddenly cut off, the momentum attained by the shuttle in entering the solenoid will be sufficient to project the shuttle bodily across the lay and into the opposite shuttle-box. Thereupon if the circuit connected with the other solenoid be correspondingly made and broken the shuttle will be again thrown across the loom. In this way by making and breaking the respective circuits in alternate succession the shuttles will be shot from side to side of the loom, pick and pick.

35 In the particular construction herein illustrated electrical connections are provided whereby when a series of shuttles are employed there will be no liability of the solenoids being energized in the event of shuttles being accidentally contained at the same time in corresponding boxes at the respective sides of the loom. Such connections are as follows: On each of the brackets f is a switch G, comprising two contact-points g g' and a lever g², one arm of which latter is extended forwardly of the adjacent shuttle-box and adapted to be actuated by the usual spring-controlled clamping-arms d in a manner to effect the shifting of the lever from one point to the other at stated times. The nose of the forward arm of the lever is beveled, as at x, to facilitate the vertical movement of the opposing clamping-arms d. Normally the switch-levers are maintained upon the contact-points g' through the action of suitably-disposed springs g². The solenoids are electrically connected with the adjacent contact-points g by means of conductors h and with the distant contact-points g' by means of conductors h'. One of the switch-levers is connected with the source of electricity H by a conductor h², the other

switch-lever being connected by a conductor h^8 with a stationary contact-piece h^4 , which is disposed on a cross-bar of the main frame in the path of a contact-plate h^5 , preferably yielding, on the back of the lay. The latter plate is connected with the source of electricity by a conductor h^6 .

The operation is as follows: Assume the upper compartment of the left-hand shuttle-box to contain a shuttle, the corresponding compartment of the other box to be vacant, and the lay to be forward. In that case the clamping-arm for said shuttle being pressed outward bears against the adjacent switch-lever g^2 and connects the latter with the point g , the electric circuit only being interrupted between the two contact-plates h^4 h^5 . The clamping-arm for the upper compartment of the right-hand box being retracted does not affect the normal position of the switch-lever adjacent thereto, and hence the circuit for the right-hand solenoid is broken at the two switches and also between the plates h^4 h^5 . Now it will be seen that during the backward stroke of the lay the plate thereon will make contact with the stationary plate, and thereby complete the electrical circuit of the left-hand solenoid, which latter, being energized, will attract the shuttle. Just before the shuttle has been fully retracted the tapered or reduced rearward end thereof permits the contiguous clamping-arm to swing inward, and in consequence the coacting switch-lever moves to its normal position, thereby breaking the circuit, whereupon the shuttle in virtue of its momentum is shot through the shed and into the opposite shuttle-box. The clamp-bar on the latter is pressed outward by the shuttle, as usual, thus shifting the right-hand switch-lever onto the contact-point g . Before the connection has been made, however, the lay is moved forward to break the contact between the two plates h^4 h^5 . In the next following backward stroke of the lay the circuit of the right-hand solenoid is completed and the operation just described repeated.

It will be obvious that as the shuttle-boxes are raised and lowered in the usual manner by the box-motion the predetermined shuttles and the clamping-bars therefor will act upon and be actuated by the electrical connections in the manner above explained. It will also be obvious that in the event of shuttles being accidentally supported adjacent to the respective solenoids both circuits will be cut off through the action of the switches and that, therefore, there will be no liability of two shuttles being simultaneously shot from opposite sides of the loom into the shed.

60. We claim as our invention—

1. In a loom, the combination with the lay provided with a shuttle-race, and the shuttle, of an electromagnet adjacent to one end of said race, an electric circuit for said magnet, and contact devices connected with said cir-

cuit and adapted to be moved into and out of contact by the action of the lay.

2. In a loom, the combination with the lay provided with a shuttle-race, and the shuttle, of a solenoid adjacent to one end of said race and in the path of the shuttle, an electric circuit for said solenoid, and contact devices connected with said circuit and adapted to be moved into and out of contact by the action of the lay.

3. In a loom, the combination with the lay provided with a shuttle-race, and the shuttle, of electromagnets adjacent to the respective ends of said race, electric circuits for said magnets, and contact devices connected with said circuits and adapted to be moved into and out of contact by the action of the lay.

4. In a loom, the combination with the lay, its race, and the shuttle, of solenoids adjacent to the respective ends of said race and in the path of the shuttle, electric circuits for said solenoids, and contact devices connected with said circuits and adapted to be moved into and out of contact by the action of the lay.

5. In a loom, the combination with the lay, the shuttle-boxes, including clamp-arms, and the shuttle, of electromagnets adjacent to said boxes, electric circuits therefor, switches in said circuits adjacent to the clamp-arms of the respective boxes, and adapted to be operated by said arms, as described, and contact devices connected with said circuits adapted to be moved into and out of contact by the action of the lay.

6. In a loom, the combination with the lay, the shuttle-boxes including clamp-arms, and the shuttle, of solenoids supported adjacent to the respective boxes and in the path of the shuttle, electric circuits for said solenoids, switches in said circuits adjacent to the clamp-arms of the respective boxes, and adapted to be operated by said arms, as described, and contact devices connected with said circuits and adapted to be moved into and out of contact by the action of the lay.

7. In a loom, the combination with the lay, the shuttle-boxes, and the shuttle, of solenoids supported adjacent to the respective boxes and in the path of the shuttle, electric circuits for said solenoids, switches in said circuits for the respective solenoids, means whereby said switches are opened and closed at predetermined intervals, and contact devices connected with said circuits and adapted to be moved into and out of contact by the action of the lay.

In testimony whereof we affix our signatures in presence of two witnesses.

WILLIAM C. EDLER.
FRANK WINDLE.
